UNITED STATES PATENT OFFICE

MARTIN KUEHNE, OF FLORAL PARK, LONG ISLAND, NEW YORK

KNITTING MACHINE

Application filed August 29, 1929. Serial No. 389,170.

This invention relates to knitting machines and has for its general object and purpose to provide certain improvements in a jacquard or flat type knitting machine such 5 as is shown in Patent No. 1,718,295, issued to me on June 25, 1929.

The essential feature of the present invention resides in the provision of two selectively operable means associated with each 10 of the needles, either of which, when operated causes a stitch forming operation of the needle in the subsequent operation of the machine. It is also an object of my present improvements to provide jacquard controlled 15 mechanism for selectively effecting the stitch forming operation of different groups of needles, in which a very compact arrangement of the several elements is provided with means for insuring their proper operation 20 by the jacquard mechanism and the positive and reliable stitch forming actuation of the individual needles.

With the above and other objects in view, 25 the invention consists in the improved knitting machine and in the form, construction, and relative arrangement of its several parts as will be hereinafter more fully described, illustrated in the accompanying drawings, 30 and subsequently incorporated in the subjoined claims.

In the drawings wherein I have illustrated 35 the essential features of a preferred embodiment of the invention and in which similar reference characters designate corresponding parts throughout the several views,—

Figure 1 is a vertical sectional view 40 through one of the needle beds and a part of the other needle bed of a jacquard or flat type knitting machine illustrating one form of my improved mechanism;

Fig. 2 is a similar sectional view through 45 the needle bed showing the relative positions of the parts after one of the jacks associated with each needle has been depressed to effect a stitch forming movement of the needle;

Fig. 3 is a similar sectional view showing 50 the relative positions of the parts after the needle has been moved in one direction to receive the yarn;

Fig. 4 is a similar sectional view showing

the positions of the parts after the other of the jacquard controlled devices has been actuated to effect the stitch forming operation of the needle;

Fig. 5 is a fragmentary top plan view of 55 the machine; and

Fig. 6 is a detail fragmentary perspective view of a part of the jacquard mechanism.

In the drawings, I have illustrated only so much of the machine as is necessary to a 60 clear understanding of the present invention, and it is understood that the invention is applicable to either a machine having two needle beds for the knitting of a double faced fabric as indicated in Fig. 1 of the drawings, 65 or may be employed on a single bed machine. As the construction of both of the needle beds and the needle operating mechanism associated therewith is the same in each instance, the detail description of one of the 70 mechanisms will suffice for both. As herein shown, the needle bed which is suitably mounted on the frame 5 of the machine is positioned in an obliquely inclined plane and 75 preferably consists of a lower section 6 and an upper section 7. Since the section 6 of the needle bed is not subject to appreciable wear due to lateral pressure of the needles or operating parts thereon, I preferably make this bed section in the form of an aluminum 80 casting. The other bed section 7, however, which is subject to considerable lateral pressure by the movable needle operating parts, is constructed of steel. These two bed sections are provided with suitably spaced 85 aligned slots as indicated at 8 and 9 respectively corresponding in number to the number of needles and in which the needles have free sliding movement.

Each needle 10 extends substantially the 90 full length of the aligned slots 8 and 9 and at its upper end it is provided with the usual latch hook 11 which receives the yarn from the yarn carrier indicated at 12 in Fig. 1 of the drawings. The lower end of the needle 95 shank is bent and returned upon itself to provide a resiliently yieldable portion 13 terminating in a downwardly projecting finger 14. Below this finger, the body portion of the needle shank has a bend 15 formed 100

therein projecting toward but spaced from the part 13 of the needle. This bend provides a stop limiting the downward movement of a wire 16 which is superimposed upon the needle shank within the slots or grooves 8 and 9 of the needle bed. This lower end of the wire 16 is provided with an upwardly projecting finger 17 positioned between the bend 15 in the needle shank and the terminal finger 14 of the part 13. Intermediate of its ends and within the groove 9 of the needle bed section 7, the wire 16 is bent upon itself to form the upstanding lug 18 projecting above the upper surface of the needle bed section 7.

Above each of the needles, a pair of jacks are mounted for sliding movement relative to each other, and with respect to the needle and are adapted to be selectively positioned whereby one or the other of said jacks is subsequently actuated to depress the part 13 of the needle and cause the terminal finger 14 thereon to engage the upstanding finger 17 on the lower end of the wire 16. As herein shown, the lower jack of each pair consists of two sections 19 and 20 respectively, the section 19 being in the form of a straight rigid steel rod of suitable diameter slidably supported in a slotted bar 21 fixed to the machine frame below the needle bed. This rod extends into one of the slots of the needle bed sections 7 and at its upper end is an opposed bearing contact against the lower arm of the part 20 of the jack which is of substantially U-shaped form as shown and has its spaced arms engaged slidably in slots provided in the steel reinforcement bars 22 and 23 respectively which are suitably fixed to the needle bed section 8. The upper arms 20 of these parts 20 terminate in upwardly projecting fingers 24.

Between the part 19 of the lower jack and the resiliently yieldable portion 13 of the needle, a separating wire 25 is interposed and has one of its ends provided with a hook 26 engaged with the wall of the bed section 6 at the lower end of the slot 8 therein which permits of a tilting or rocking movement of said wire but prevents its longitudinal shifting movement relative to the needle bed. Thus shifting of the needle relatively to the bed in the sliding movement of the jack rod 19 is prevented. A similar relatively fixed separating wire 27 is also interposed between the upper side of rod 19 of the lower jack and the downwardly projecting upper end 29 of the upper jack 28 which is disposed in the same vertical plane as the lower jack rod 19 and is slidably through one of the slots in the steel reinforcing bar 30 secured to the bed section 6. This jack rod 28 is also provided with an upstanding finger 31, said rod being likewise movable through one of the slots of the bar 21, such sliding move-

ment of the rod 28 being yieldingly resisted by a suitable leaf spring indicated at 32.

While the particular jacquard mechanism which operates upon the jack rods 19 and 28 constitutes no essential part of my present invention, I have herein shown a rotatably supported drum 33 of any desired polygonal form in cross section. The jacquard "cards" which are flexibly connected together by means of suitable links in the usual manner, as herein shown, are in the form of T-shaped bars 34, the central leg of which is adapted to project radially with respect to the center of the drum 33 when the head of said bar is positioned upon one of the faces of the drum as clearly shown in Fig. 1 of the drawings. This radially extended part of the bar 34 carries two sheet metal strips 35 and 36 respectively, suitably secured thereto and projecting on opposite sides of the bar. The longitudinal edge portions of these strips are spaced apart and said edges are transversely slit or cut at equally distant spaced points to provide bendable tongues 37 thereon. These tongues normally extend at right angles to the opposite side faces of the central web of the bar 34, and selected tongues of the spaced apart edges of the two metal strips are adapted to be bent downwardly in parallel relation to the opposite sides of the bar as clearly shown in Fig. 6 of the drawings, thus providing spaces to receive the lower ends of the jack rods 19 and 28. It will, therefore, be understood that in the operation of the jacquard mechanism, the individual needles mounted on the needle bed of the machine will be selectively positioned in accordance with the relation which the tongues on the edges of the spaced metal strips bear to each other and to the head of the T-shaped bars 34. Thus the tongues of the outermost strip 36 which have not been bent will strike the lower ends of certain of the jacks 19 and 28 and thereby move the jack parts 28 and 20 to the highest positions on the needle bed.

Where tongues of this outer strip have been bent downwardly but the opposed tongues of the strips 35 have not been correspondingly bent, other jacks will strike these latter tongues and they will be moved to the second or intermediate position, while in those instances where the opposing tongues of the two metal strips have both been bent as shown at the left of Fig. 6, the jack rods opposed thereto will not be moved and will remain in the lower position. These three positions are indicated by the lines A, B, and C respectively in Fig. 5 of the drawings.

A cam plate 38 is slidably mounted in any suitable manner for longitudinal movement over the two sections 6 and 7 of the needle bed. The under side of this cam plate is provided on the lower portion thereof with two series of cam lugs or projections 39 and 40 respectively, the cam lugs in each series

being arranged in pairs spaced from each other both transversely and longitudinally of the cam plate. The cam lugs 39 are adapted to cooperate with the fingers 24 of the jack parts 20, while the series of cam lugs 40 are adapted to cooperate with the fingers 31 on the jack rods 28. Above these series of cam parts 39 and 40, there is further provided upon the under side of the plate 38 and near its upper edge, the longitudinally spaced groups of cam projections indicated at 41, said projections in each group forming an inverted V-shaped cam way 42 similar to that shown in my issued Patent 1,718,295. It will further be noted that one pair of the cam lugs in each of the groups 39 and 40 is in alignment transversely of the plate 38 with one of the cam ways 42. These cam ways are adapted to receive the upwardly projecting parts 18 of the wires 16 associated with the individual needles so that in the movement of the plate 38 across the needle bed, sliding movement will be transmitted to certain of the needles whereby the desired 25 stitches in accordance with the predetermined pattern will be formed.

In the operation of the mechanism above described, assuming that the pairs of jacks associated with each needle have been selectively actuated by the jacquard mechanism, it will be understood that the fingers 24 and 31 of the jack parts 20 and 28 are positioned in line with the path of movement of the several pairs of cam projections 39 and 40 on the cam plate 38, as determined by the particular jacquard card which was moved into cooperative relation with the lower ends of the jacks, the cam plate 38 is now actuated and shifted over the surface of the needle bed. Assuming that this plate in Fig. 5 of the drawings is moving from left to right, it will be apparent that the three pairs of lugs 39 will engage the fingers 24 of the jack parts 20 which may have been moved to the 45 positions indicated by the lines A, B, and C, while the other series of cam lugs 40 will engage the fingers 31 of the jacks 28 which are disposed in corresponding positions. As shown in Figs. 2 and 3 of the drawings, when 50 one of the lugs 39 engages a finger 24 on one of the parts 20, the upper arm of this jack part is depressed into the slot of the bar 22, the said jack part having its fulcrum bearing on the bar 23 at the lower end of 55 the slot therein. The lower arm of this jack part is thus forced downwardly against the end of the wire 25 which in turn is in bearing contact upon the end portion 13 of the needle, thus depressing the terminal finger 14 60 and engaging the same behind the upstanding finger 17 on the wire 16. This resilient end portion of the needle will be depressed and similarly engaged with the lower end of the wire 16, when the finger 31 on one of the 65 upper jacks 28 is engaged by one of the

cam projections 40. The end 29 of this jack rod will bend the wire 27 downwardly, thus tilting or rocking the lower jack rod section 19 relative to the guide bar 21, and thereby depressing the end portion 13 of the needle. 70

In such operation of course the part 20 of the lower jack remains in normal position.

As the properly positioned jacks are thus operated in the sliding movement of the cam plate and the fingers 14 and 17 engaged with each other, the upstanding portions 18 of the rods 16 enter the cam ways 42 of the respective groups of cam parts on the upper portion of the plate 38 and by coaction with said cam parts, first shift the wires 16 and therefore also the needles which are interlocked therewith upwardly in the grooves or slots of the bed plate so as to cause the latch hooks 11 of such needles to engage and receive the yarn. After the projections 18 have moved 85 through the apex portions of the cam ways 42, such movement is reversed and the wires 16 are forced downward and the lower end of the said wires bearing on the projections or lugs 16 of the needle bars, also of course moves the 90 needles downwardly in the slots of the bed plate as will be readily understood from reference to Figs. 3 and 4 of the drawings, thus completing the stitch forming operation. 95

As in my issued patent, there is further provided at the opposite ends of the cam plate 38, on the under side thereof adjustable members 43, and as shown in Fig. 5 of the drawings, when the cam plate is moved from left to right, the members 43 at the left-hand end of said plate beyond the cam projections 39 and 40 are disposed in an oblique inclination, while the members 43 at the right-hand end of the cam plate are positioned parallel to the path of movement of said plate and above the respective series of cam projections 39 and 40. Thus after all of the needles have been actuated and at the end of the movement of the cam plate 38, the edges of the obliquely inclined members 43 will engage 110 the fingers 24 and 31 respectively of the two series of jacks and return said jacks to their normal positions with all of these fingers disposed in the same position horizontally of 115 the bed plate and below the respective series of cam projections 39 and 40, thus placing the jacks in position to be again actuated by another jacquard card.

As the cam plate is alternately shifted in opposite directions across the bed plate, it will be understood that the yarn carriers are automatically shifted to positions at relatively opposite sides of the apex portions of the cam ways 42, in the manner indicated in 120 my issued Patent 1,718,295.

From the foregoing description considered in connection with the accompanying drawings, the construction, operation, and several advantages of my improved knitting machine 125 will be clearly and fully understood, and it 130

will be apparent that by means of my present improvements, a greater range of selectivity in the knitting of multi-colored fabrics of intricate design, is obtained. It will also be seen that by means of the particular mounting and arrangement of the various cooperating elements of this mechanism that positive and reliable actuation of the individual needles is assured. However, while I have herein shown and described one practical embodiment of the essential features of my present improvement, it will nevertheless be understood that the same might also be incorporated in various other mechanical forms, and I, therefore, reserve the privilege of resorting to all such legitimate changes therein as may be fairly embodied within the spirit and scope of the invention as claimed.

I claim:

1. In a jacquard knitting machine, a needle bed and needles slidably mounted therein, an actuating member for each needle in constant superimposed contact throughout its length with the needle, means including a part angularly movable relative to the actuating member and the needle to connect the member and needle for unitary sliding movement on the needle bed, and a member movable over the needle bed provided with spaced operating means for said movable connecting parts and for the needle actuating members respectively.

2. In a jacquard knitting machine, a needle bed and needles slidably mounted therein, an actuating member for each needle superimposed throughout its length thereon, said needle having a part angularly movable relative to the needle axis to releasably engage a part on said actuating member and connect said needle and member for unitary sliding movement, jacquard controlled means associated with each needle for moving said part to a position to establish such connection, and a member movable over the needle bed provided with spaced operating means for said jacquard controlled means and the needle actuating members respectively.

3. In a jacquard knitting machine, a needle bed and needles slidably mounted therein, an actuating member for each needle superimposed throughout its length thereon, said needle having a part angularly movable relative to the needle axis to releasably engage a part on said actuating member and connect said needle and member for unitary sliding movement, jacquard controlled means associated with each needle for moving said part to a position to establish such connection, the needle shank adjacent to said movable part having an angular projection for engagement by one end of the actuating member to move the needle in one direction, and a member movable over the needle bed provided with spaced operating means for said

jacquard controlled means and the needle actuating members respectively.

4. In a jacquard knitting machine, a needle bed and needles slidably mounted therein, an actuating member for each needle superimposed thereon, the needle shank having a reversely bent resiliently yieldable end portion, said end portion of the needle and the actuating member having relatively movable parts for engagement with each other to connect said needle and actuating member for unitary reciprocating movement, the needle shank being further provided with an angularly projecting part for engagement by one end of the actuating member to move the needle in one direction, jacquard controlled means associated with each needle for moving one of the said parts to establish such connection, and a member movable over the needle bed provided with spaced operating means for said jacquard controlled means and the needle actuating members respectively.

5. The knitting machine described in claim 4 in which said jacquard controlled means includes independently movable elements each adapted to act upon the resilient end portion of the needle and selectively movable by the same jacquard card to positions for engagement and operation at relatively different times by spaced parts of the operating means carried by said movable member.

6. In a jacquard knitting machine, a needle bed and needles slidably mounted therein, an actuating member for each needle superimposed thereon, the needle shank having a reversely bent resiliently yieldable end portion, said end portion of the needle and the actuating member having relatively movable parts for engagement with each other to connect said needle and actuating member for unitary reciprocating movement, the needle shank being further provided with an angularly projecting part for engagement by one end of the actuating member to move the needle in one direction, jacquard controlled means associated with each needle for moving one of the said parts to establish such connection, a member movable over the needle bed provided with spaced operating means for said jacquard controlled means and the needle actuating members respectively, said jacquard controlled means including independently movable elements each adapted to act upon the resilient end portion of a needle and selectively movable by the same jacquard card to positions for engagement and operation at relatively different times by spaced parts of the operating means carried by said movable member, said operating means comprising spaced groups of cam projections, the projections in each group arranged in spaced pairs and out of alignment with each other for coaction with the respective selectively positioned elements of the jacquard controlled means.

7. The knitting machine described in claim 6 in which the operating means on said movable member for the needle actuating members comprises spaced groups of cam projections corresponding with the number of said spaced pairs of cam projections and providing cam ways for receiving angularly projecting parts of said actuating members to impart reciprocating motion thereto.

10 8. The knitting machine described in claim 6 in which means are fixed upon the needle bed and interposed between the jacquard actuated elements and between one of said elements and the resilient end portion of the 15 needle to prevent shifting of the needle in the actuation of said elements or the transmission of movement by one of said elements to the other.

10 In testimony that I claim the foregoing as my invention, I have signed my name hereto.
20 MARTIN KUEHNE.
